[57] CLAIM

The ornamental design for a glenoid fossa resurfacing implant for the temporomandibular joint, substantially as shown.

DESCRIPTION

FIG. 1 is a bottom perspective view of the glenoid fossa resurfacing implant for the temporomandibular joint showing our new design;

FIG. 2 is a top perspective view thereof;

FIG. 3 is another bottom perspective view thereof;

FIG. 4 is a cross-sectional view taken on line 4—4 of FIG. 3;

FIG. 5 is a front side elevational view thereof;

FIG. 6 is a right side elevational view of FIG. 5;

FIG. 7 is a rear elevational view of FIG. 5; and

FIG. 8 is a left side elevational view of FIG. 5.
